UNITED STATES PATENT OFFICE

91,423

DESIGN FOR AN APPAREL BELT FRONT

William Forstner, Irvington, N. J.

Application October 10, 1933. Serial No. 49,449

Term of patent 3½ years

To all whom it may concern:

Be it known that I, WILLIAM FORSTNER, a citizen of the United States, residing at Irvington, in the county of Essex and State of New Jersey, have invented a new, original, and ornamental Design for Apparel Belt Front, of which the following is a specification, reference being had to the accompanying drawing, forming a part thereof, and in which:

Figure 1 is a plan view of an apparel belt front, showing my new design.

Figure 2 is an edge view of the same.

This design consists of two similar woven wire fabrics having smoothly curved longitudinal edges, their outer end portions being contracted in width, producing a ruffled appearance, and

having their extremities bound by flat ferrules to which are attached permanent loops to be secured to the belt ends.

The inner adjacent ends of these elements are similarly bound and connected to transversely curled members, one of which is provided with a hook and the other with an elongated eye in which the hook is detachably engaged.

Midway the central portion of each of the meshed elements is a raised button-like ornament.

I claim:

The ornamental design for an apparel belt front, as shown and described.

WILLIAM FORSTNER.
